Inventor:

Jacob Jahnens.

UNITED STATES PATENT OFFICE.

JACOB JAHRAUS, OF BUFFALO, NEW YORK.

IMPROVEMENT IN FAUCETS AND VENTS.

Specification forming part of Letters Patent No. 40,044, dated September 22, 1863.

To all whom it may concern:

Be it known that I, JACOB JAHRAUS, of the city of Buffalo, and State of New York, have invented a new and Improved Beer-Faucet; and I do hereby declare that the following is a full and exact description thereof, reference being made to the accompanying drawings, making a part of this specification, in which—

Figure I is a section of my improved faucet. Fig. II represents the ventilating-plug as standing in the top of beer-barrel with a cord leading to the faucet. Fig. III is a transverse section of the discharge-nozzle.

The nature of this invention relates to the construction and arrangement of a compound discharge-nozzle, which will freely discharge the liquor through its outer cylinder, when the valves are raised, and which allows a quantity of liquor to remain in the inner cylinder to be forced out through a small aperture in its bottom in the act of closing the valves.

Letters of like name and kind refer to like parts in each of the figures.

A represents the main body or barrel of the faucet through which the liquor is drawn.

B is a valve-cylinder, which is screwed into the bulb a', (or large projecting end of the faucet.) It projects upwardly and at right angles thereto, or nearly so.

C is a valve-stem, and C' and C² conical valves connected therewith. The valve-stem works through a stuffing-box, D. Conical valve-seats are made in the bulb, into which the valves tightly fit when closed.

E is a lever, acting upon the valve-stem, for opening and closing the valves.

F is a post projecting upwardly from the main body of the faucet for the support of the lever. It has a pin or fulcrum shaft in the top, as shown at f', upon which the lever works.

The discharging-nozzle has two cylinders, G and H. These two cylinders are connected together at the top and screw into the under side of the bulb, as shown at I. The outer cylinder, G, is open at the bottom. The inner cylinder, H, is made much smaller than the outer, so as to leave ample room for the liquor to pass between the cylinders and out at the bottom of the outer cylinder. The inner cylinder is made flaring at its upper end, so as to form a tight connection with the outer at its extreme upper end.

Apertures or holes h' are made through the flaring part of the inner cylinder to allow the beer or liquor to flow through into the outer cylinder.

A stationary head, h², is put into the lower end of this inner cylinder, through which head there is a very small hole, as shown at j.

K is a hollow piston-rod, which screws into the lower end of the valve-stem C, as shown in the drawings, and projects downwardly so as to act as a forcing-piston in the cylindrical part of the inner cylinder. Small holes K' are made through this hollow piston-rod to allow the liquor to flow through and down into the cylindrical chamber below at such times when the piston-head may stand partly below the holes h'.

A puppet-valve, L, is connected with this piston-rod. It has a long valve-rod, n, which passes up through the piston-rod, and has a large head, n', on the top. The red lines show the valves and piston, &c., in their lowest position, the valves being closed and the flow of the liquor shut off.

M represents a ventilating-plug, which is inserted into the upper head of the barrel containing the liquor. A smaller plug, M', is projected at right angles therefrom, with an aperture, O, which opens into the external air. A conical valve, P, works on the outside of this small plug.

Q is a spiral spring, which is placed on the plug in order to force the valve back to its place, as represented by the red lines P', when the faucet is shut.

R is a string or cord which connects this valve with the end of the lever E.

S is a section of the cask which contains the beer or other liquor.

Operation: The faucet is inserted into a barrel or cask, containing the liquor to be drawn, in a common manner. The red lines in Figs. I and II show the valves all closed and the flow of the liquor shut off. Now, lift on the handle of the lever E and raise the valves c' c² but slightly and the liquor will flow through the faucet, passing through the holes h' into the outer cylinder, G, and thence into the glass. If the lever is raised high enough to bring the head of the piston K above the holes h', then the liquor will quickly fill the inner cylinder, H, below the holes h', and pass

through the holes h' into the cylinder G, and thence into the glass or vessel into which it is to be drawn. When the lever E is pressed down, so as to close the valves, the piston K is also forced down at the same time into the inner cylinder, H, and thereby forces the liquor, which had collected therein, through the small aperture j into the liquor already in the glass, thereby producing a lively sparkling foam on the surface and imparting life and sharpness to the body of the liquor in the glass. If the lever is not raised high enough to raise the piston-head above the holes h' , which will be the case when you desire to draw the liquor very slow, then sufficient liquor will pass through the holes K' to fill the cylinder H below the piston, so that when the piston descends it will force out, through the small hole j , what liquor there had collected in the cylinder, and produce the same effect as before stated. When the lever is raised so as to

open the valves $c' c^2$, it will pull upon the string R sufficient to move the valve P back far enough to open the vent. When the lever is pressed down so as to shut the valves, it loosens the string sufficiently to allow the spring Q to force the valve P back to its place in a manner to close the vent.

I claim as my invention--

1. The compound discharge-nozzle composed of the cylinders G and H, in combination with the hollow valve-piston K, (with or without the holes K'), valve-stem C, and valve $c' c^2$, and lever E, arranged and operating for the purposes and substantially as described.

2. The valve P, arranged and operating upon the outside of the ventilating-plug M', substantially as set forth.

JACOB JAHRAUS.
